HENRY H. TALBOYS, OF MILWAUKEE, WISCONSIN, ASSIGNOR TO NORDBERG MANUFACTURING COMPANY, OF MILWAUKEE, WISCONSIN, A CORPORATION OF WISCONSIN.

MACHINE FOR RAISING AND SHIFTING RAILWAY TRACKS.

Application filed October 31, 1925. Serial No. 66,026.

Nature and purposes of the invention.

In the maintenance of railway systems, it frequently becomes necessary to raise the tracks, so that ballast may be tamped under the cross ties to support the tracks in their raised position, to bring them up to the desired level, and it likewise frequently becomes necessary to shift the tracks laterally to straighten the tracks, for the purpose of enabling a more satisfactory operation of the trains of cars moving thereover to be effected.

These results have heretofore been secured generally by the employment of a vast amount of manual labor, and have required a great deal of time for their accomplishment. From the inception of the railroad, it has been the general practice in raising the tracks, to use a number of lever or other power operated lifting jacks, which are set under the rails and actuated slowly by hand to raise a section of the track from its embedded position in the roadway, so that the desired grade could be established. Again, when it was desired to straighten the track, it has required the combined efforts of a gang of sixteen or more men using crow-bars to move the track laterally inch by inch, and this latter often proved difficult of performance by reason of inability to maintain a fixed fulcrum for the crow-bars. As before indicated, the practice which was followed for so many years has now become costly by reason of present labor conditions and the time consumed in effecting it, but has necessarily been continued in the absence of any known better manner of achieving the work.

My invention is embodied in a machine which operates automatically in a most expeditious manner to raise and shift railway tracks, so that the time factor which heretofore has contributed so greatly to the cost of the work is entirely eliminated. In other words, that work which heretofore has required a considerable amount of time for its performance, is now effected instantly by means of my improved machine, both in the raising and lateral shifting of the track. And these results are achieved with the aid

of a small operating crew only instead of the large gang of men heretofore required.

The invention comprises a machine which may be propelled under its own power over the track from place to place, and which is adapted to be clamped to the rails so as to lift the track together with the entire machine when the lower end of a vertically movable boom or spud, actuated by the power unit of the machine, is pressed upon the bed of the roadway. By inclining or tilting the boom or spud from its vertical position before the track has been raised from the roadbed, and then lifting, a section of the track may be moved laterally to a new position, without disturbing the relation of the machine to the track upon which it is clamped. Then after again raising the boom or spud, the machine may be moved to another section of track, and the operations repeated. The operation of the machine is performed in but an instant of time.

While the improved machine finds the highest fulfillment of its purposes when used in connection with the roadways of standard railway systems, and has met with immediate favor by reason of its quick action and production of the desired results at a greatly reduced cost, and its capacity for effective operation in the performance of its functions without delay to traffic, it has also met with great industrial favor where the tracks have but a temporary location, as on dumps and excavating and filling work, and in mining. The invention, therefore, has a range of very wide application in this art.

Having thus outlined the general nature and purposes of my invention, I will reserve for statement later on in this specification the details of my invention, in the matter descriptive of what is shown in the accompanying drawings, and will point out the novel features of the invention, in the claims appended to this specification.

The drawings.

In the accompanying drawings: Figure 1 is a plan view showing in general outline a car adapted for travel along

a railway and supporting a machine constructed in accordance with my invention.

Fig. 2 is a view in side elevation of the structure, looking from the right hand side.

Fig. 3 is a view in elevation of the rear end of the same, looking from the left of Fig. 1.

Fig. 4 is a vertical sectional view longitudinally of a portion of the machine, on the line 4—4, Fig. 1, and showing the transmission braking device.

Fig. 5 is a view in elevation from the left, Fig. 1, showing the lever and connections therewith for controlling the travel of the car and the spud or boom actuating device.

Fig. 6 is a side view of the primary driving shaft clutch locking devices.

Fig. 7 is a view in elevation of the locking lever of the same, and illustrating its action.

Fig. 8 is a view in side elevation, partly in section, showing the friction brake to prevent accidental downward creeping movement of the spud during the travel of the car.

Fig. 9 is a right hand end view, partly in section, showing the cross-bed, with the chair and connections for directly carrying the load when a section of the track is raised.

Fig. 10 is a view in elevation of the holding dog for the car travel and spud actuating clutch, operated by the lever shown in Fig. 5.

Figs. 11, 12, 13, and 14, are diagrammatic views from the right side of the car showing the different positions of the clamp operating levers and lifters and their holding latches.

The car structure and the motive power.

In the drawing, the numerals 10 and 10', respectively, indicate the frame and the car and a cross-bed thereon, upon which the elements comprising my invention are mounted. The said frame is supported by flanged wheels 11, the axles of which are journaled in boxes 12, attached to the frame, the said wheels resting upon the rails 13, to position the car laterally upon the track, and permit its movement from place to place. The front axle preferably is journaled in a swiveled bolster.

A power plant or unit 14, of any suitable design and construction is mounted upon the frame at the forward end of the car, the transverse shaft 15 of the power plant being connected to the primary driving shaft 16, which is journaled in the gear box 17, the latter being positioned toward the rear end of the car, through any suitable means, as, for example, a sprocket 18 which may be clutched to the shaft 15, and a sprocket 19, shown as mounted on the projecting end of the shaft 16, and a sprocket chain 20 passing about the said sprockets, so that the motion of the shaft 15 of the engine is transmitted

to the primary driving shaft 16, through the said sprocket chain. From the latter shaft, the operating elements of the machine receive their several impulses, through various connections to be hereinafter described. The gear box 17 is to be packed with grease.

Propelling the car.

The car is propelled along the track by the engine, indirectly, through a car driving shaft 16', likewise journaled in the gear box 17, and aligned with the said primary driving shaft 16. The projecting end of the car driving shaft 16' is provided with a sprocket 21, and the rear axle of the car with a sprocket 22, such sprockets being operatively connected by a sprocket chain 23. The shafts 16 and 16' are adapted to be coupled for driving the car in either direction through an arrangement of reversing gears, which will be described later.

Arresting the travel of the car.

Brake shoes 24, are arranged to engage the fore wheels 11 of the car, to arrest the travelling movement of the car, when desired. Such brake shoes are moved by the throw of eccentrics 25, mounted upon a transversely arranged oscillating brake shaft 25', which latter is provided with a radial arm 26, the free end of the said arm being connected to one end of a cable 27, passed about a rope sheave 28 at the rear end of the car, the other end of the cable being connected to the short horizontal arm 29 of a bell-crank lever pivoted at 30, upon a bracket 31 on the platform of the car. The lever arm 32 of the bell-crank extends upwardly, within easy reach of the operator standing on the platform of the car, so that by swinging the bell-crank lever about its pivotal point, the brakes may be set and released as desired.

Standards 33, rising from the platform of the car, support at their upper ends a hand rail 34, at one side of which is secured a brake iron 35, in the notches of which a detent 36 on the lever arm 32 is adapted to catch, so as to hold the brakes 24 in engagement with the wheels of the car, when braking pressure is applied through the devices described. A contracting spring 37, attached at one end to the arm 26, and at the other to the frame of the car, serves to reverse the motion of the brake shaft, and relieve the wheels 11 from braking pressure, so that the car may be moved along the track, when the detent on the lever arm 32 is released from engagement with the notches on the brake iron 35.

Means for clamping the car to the track.

The car having been moved to that section of the track which it is desired to ele-

vate, or to elevate and shift laterally, it is necessary that the car be clamped to the rails, so that the latter and the cross ties may be lifted bodily from the roadbed.

At the opposite sides of the car, I arrange floating clamp beams 40 and 41, directly over and parallel with the rails, and in the space between the front and rear wheels at each side of the car. These clamp beams are provided upon their underside at each end with a plurality of transversely standing depending ears 42, which latter are perforated for the reception of pins upon which are pivoted the upper ends of pairs of toggle links 43 and 44, the lower ends of which are pivoted to the upper ends of pairs of centrally pivoted, crossed, rail clamps 45 and 46, respectively, each of the latter being formed at its lower end with a hook 47, 48, positioned at opposite sides of the rail, and adapted, when the toggle links are actuated by raising the clamp beam, to move the hooks of a pair toward each other, to engage under the head of the rail, and firmly clamp the latter. The sets of toggle links and the rail clamps form lazy-tong structures, of which four are employed in the machine.

A rod 49, having a length approximately 30 that of the clamp beams 40 and 41, is arranged to form the pivot for the crossed rail clamps 45 and 46.

Clamp thrust bars 50 and 51, diagonally disposed in crossed pairs, extend transversely of the car, with their upper ends connected to a fixed part of the frame structure so as to have a pivotal movement, and their lower free ends perforated to receive the said rods 49, so that any lateral thrust 35 which may occur in operation is taken directly by the said clamp bars through the frame of the car, instead of by the flanges of the wheels 11, and stability assured. The said thrust bars act to hold the rail clamps 40 to a fixed though slightly arcuate path of vertical movement. Abutments 52 are arranged on the frame at the upper ends of the thrust bars, so as to relieve the pivots of the latter from strain, when the bars are subjected to thrust.

Equalizing chains 53, 54, extend between the ends of the clamp beams 40 and 41 and the frame, so as to preserve the parallelism of the said beams, and limit the range of their downward movement at all times.

A squared shaft 60 extending transversely of the car, is provided at its right hand end with a clamp lever 61, and near each end with a short arm 62, each of the latter being pivotally connected to the upper end of a curved link 63, the lower end of the link being connected to a pin 64, set in the clamp beam, and working in a slot in the said link, when the said beam is moved by other means. By throwing the clamp lever 61 toward the

rear of the car, the clamp beams 40 and 41 are lifted and the toggle links 43 and 44 straightened, so that the hooks at the ends of the rail clamps 45 and 46 are caused to engage the rails, in the manner previously 70 described. In such movement of the clamp lever 61, it wipes past a fixed spring-latch 65, by which it is retained in the position to which it has been moved. Release of the latch 65 by foot pressure from its engagement with the clamp lever, will permit the said lever 61 to be returned to its former position. This reverse action will permit the clamping beams 40 and 41 to be lowered thus collapsing the toggles and withdrawing 80 the rail clamps from engagement with the rails.

The short arms 62, just referred to, resting upon chairs 62', carry the weight of the track when it is raised in the operation of 85 the machine, as will be described later. The purpose in providing the curved links 63 is to enable their points of connection with the short arms 62 to pass over the center line of the shaft 60, in the rail clamping movement 90 of the lever 61, so as to relieve the holding latch 65 for the said lever from the strain incident to the support of so great a weight, and transfer it to the said arms and the chairs in which they are seated.

Means for raising the rail clamps.

It is designed that the entire rail clamping structure shall be raised and maintained in elevated position, clear of the rails, while the car is traveling, or is being moved from place to place, but is adapted, as before indicated, to be lowered to engage the clamps 45 and 46 with the rails when desired. Means are provided for elevating the rail clamps to the full extent, as when the car is traveling along the railroad, and also for elevating them partially but sufficiently to clear the rails, as when the car is moving from place to place on a section of the track 100 which is to be shifted.

The lower swinging ends of the clamp thrust bars 50 and 51 are perforated so as to receive the rods 49, previously mentioned, and may be positioned in the length of the rods by tubular spacers 49', slipped over the rods 49. To the ends of the thrust bars 50 and 51, near the points of their connection with the rod 49, chains 70 and 71 are attached at one end, the other ends of the said chains being connected to the opposite ends of a clamp lifter bar 72, one at each side of the car. The clamp lifter bars are provided with an upstanding central arm 73, the upper end of which is pivotally connected to the short arm 74, of a clamp lifter lever 75, mounted on the right end of a transversely extending shaft 76. A similar short arm on the other end of the shaft 76, has a like connection with the clamp lifter bar at the 110 115 120 125 130

other side of the car. The arm 73 of the clamp lifter bar is shown as provided with a vertical slot 77, but such slot is without function other than to lessen the weight of the clamp lifter bar in which it is formed.

By throwing the clamp lifter lever 75 toward the rear of the car, until the said lever assumes an approximately upright position, the pull of the clamp lifter bar 72 on the chains 70 and 71, will raise the rod 49 and break the toggles of which the rail clamps 45 and 46 form a part, and effect the disengagement of the said clamps from the rails.

15 The clamp lifter lever 75, or the shaft 76 on which the said lever is mounted, is provided with a heel 78, which is cut away at its free end so as to form a shoulder 78' upon its inner face. When the lever 75 is thrown 20 to the rear, the shoulder on the heel 78 will engage a fixed spring-latch 79, and lever will be held in the approximately upright position to which it is moved, and so sustain the rail clamping devices in but slightly elevated 25 positions. The said latch 79 has formed thereon a lateral projection 80, adapted to be pressed upon by the foot of the operator, to withdraw the said latch from its engagement with the clamp lifter lever 75, and so permit 30 the rail clamping devices to be lowered into operative positions, as will be understood from what has been stated hereinbefore. At such time, the rail clamps 45 and 46 are separated, and in position to be brought into 35 gripping engagement with the rails, when the clamp lever 61 is thrown to raise the clamp beams 40 and 41 and straighten the rail clamp toggles. The rods 49, on which the rail clamps are pivoted, and the lower 40 ends of the clamp thrust bars 50 and 51, are raised slightly at the same time.

45 The movements of the clamp beams and clamp lifter bars, and their operating levers, in positioning the parts, are diagrammatically shown in Figs. 11 to 14, to which reference may be had at this time.

In Fig. 11 the clamp beam lever 61 and the clamp lifter bar lever 75, are in their extreme forward positions, and the clamp beams 40 and 41 and clamp lifter bars 72 are down, with the clamps 45 and 46 in position to be brought into engagement with the rails. By throwing the clamp beam lever 61 to the left, as shown in Fig. 12, the clamps are caused to engage the rails, and the track may then be lifted by the devices which will be described presently.

By releasing the clamp beam lever 61 to the forward position shown in Fig. 13, the clamps are caused to release their grip on the rails. The car may now be moved to another near point, but to avoid interference, the clamps are slightly raised to their intermediate position, clear of the rails, and this is effected by throwing the clamp lifter bar

lever 75, into its approximately upright position, as shown in Fig. 13. When the car is positioned anew, the clamp lifter bar lever 75 is released by withdrawing the latch 79 from engagement with shoulder 78' on the heel 78, 70 and the said lever swings forward to again position the clamps for engagement with the rails, by another backward swing of the clamp beam lever 61 to the position shown in Fig. 12.

75 The clamp beam lever 61 is provided upon its inner side with a lateral projection 61', which will sweep over the end of the heel 78 of the clamp lifter bar lever 75, in the backward throw of the clamp beam lever 61, 80 as shown in Fig. 12, at the time that the clamp lifter bar lever 75 is in its forward position. But with the said lever 75 in the position shown in Fig. 13, as at the conclusion 85 of work upon a certain section of track, and the rail clamps in their intermediate positions, the heel 78 stands interposed in the arcuate path of movement of the lateral projection 61' on the lever 61, and in the backward movement of the latter, the lever 75 is 90 carried with it through engagement of the said projection with the heel, and the said lever is moved to its most rearward position, as indicated in Fig. 14. In this joint movement 95 of the two levers 61 and 75, the clamp beams, the clamp lifter bars, and the rail clamps, are elevated to their highest positions, so as to clear any obstructions which might impede the travel of the car, when a long run is to be made.

100 In such joint movement of the levers 61 and 75, the inner faces of the projection 61' of the clamp beam lever and the heel 78 of the clamp lifter bar lever lie in the same vertical place, and together press and hold the 105 spring-latch 79 out of position to engage either lever, as is shown in Fig. 14. At such time, both of the said levers, and the entire rail clamping devices, are held by the spring latch 65, which engages the lever 61. In releasing the levers upon the car reaching a new position on the roadway, the said levers should be taken, one in each hand, and the latch 65 thrown out, to lower the clamping 110 devices for further operations.

The track lifting mechanism.

115 After the rails have been clamped, the track is lifted by the action of a vertically moving spud or boom 90, mounted in a spud carriage 91, supported by and adapted to be moved transversely of the car on two cross rails 92 and 93, formed as parts of the crossbed 10', so as to position the shoe 94 pivoted 120 on the lower end of the spud at such point between the rails as will enable the most satisfactory operation to be effected, as may be determined by the condition of the track and roadbed, and the direction in which it is desired to throw the track.

Referring again to the gear box 17, one end of the main transmission shaft 95 is journaled therein, the said shaft being journaled at its other end in a bearing on the frame at the other side of the car. Within the gear box 17, and fixed upon the primary drive shaft 16, are spaced gears 96 and 97, and loose upon the main transmission shaft 95, are like gears 98 and 99. The gears 96 and 98 are in mesh, but the gears 97 and 99 are connected through an idler 100, so as to rotate reversely. The opposed hubs of the gears 98 and 99, are provided with clutch faces, which are adapted to be engaged by the double-faced clutch member 101 splined upon the main transmission shaft 95, so that the said shaft may be driven in either direction, dependent upon which face of the clutch member 101 is engaged with either gear 98 or 99. Thus, the motion of the engine shaft is transmitted to the main transmission shaft 95. When one set of gears is engaged, the other runs idle.

In connection with this description of the operation of the main transmission shaft from the primary driving shaft, it may be stated that the car drive shaft 16', within the gear box 17, has fixed thereon spaced gears 102 and 103, in mesh with like gears 104 and 105, loose upon the main transmission shaft. These gears are proportioned and arranged so as to form a speed changer. The opposed hubs of the gears 104 and 105, are formed with clutch faces adapted to be engaged by a double-faced clutch member 106, splined upon the main transmission shaft, so that the car may be propelled in either direction at different speeds, through the sprocket 22 on the rear axle, according to which gear 104 or 105, is engaged by the sliding clutch member 106, and the direction of rotation at the time of the main transmission shaft.

The said clutch member 106 is controlled as to either engaging position, or its neutral position, by a hand lever 110, arranged within the reach of the operator on the platform of the car, and pivoted near its lower end. A link 111, adapted to be connected to the said hand lever above its pivotal point, and connected to an arm 111¹ on the shaft of the clutch, effects the sliding movement of the clutch member 106, in the throw of the lever 110 at the desired times. The hand lever 110 is forked at its lower end to embrace a fixed shaft 111² to which it is pinned, so that it may be pivoted either toward the front or the rear of the car. The link 111 is supported at the point of its connection with the lever 110 by an arm 111³ mounted loosely upon the shaft 111², which arm is provided at its upper end with a stud 111⁴, adapted to enter a hole 110¹ in the lever 110, when the latter is thrown toward the front, and in the following movement of the said

lever to the right or left, the splined clutch member 106 will be shifted to engage one or the other of the gears 104 or 105, and the car will be propelled accordingly.

The hand lever 110 normally occupies a neutral position, as indicated in Fig. 5. Its second position is that of controlling the travel of the car, as just described. Its third position in effecting movement of the spud 90 will be described later. The clutch member 106, likewise has two operative positions and one of neutrality, determined by the movement of the lever 110.

In a like manner, the direction of rotation of the main transmission shaft 95, is controlled by a second pivoted hand lever 112, acting upon the clutch member 101, through a connecting link 113, pivoted at one end to the lever 112, and at the other to an arm or locking lever 112¹, fixed intermediate its ends to the shaft operating the splined clutch member 101, which has two operative positions, being engaged with one or the other of the clutch faces on the gears 98 and 99, loose upon the main transmission shaft 95. The locking lever 112¹ is provided with a roll adapted to wipe over the upper end of a spring-pressed plunger 112², such end of the plunger being cut away oppositely from the longitudinal center of the lever 112¹, so as to form inclined surfaces over which the said roll will ride and hold the lever in either of its positions, and retain the engagement of the clutch member 101 with the gear to which it is coupled in the throw of the hand lever 112.

The other end of the main transmission shaft 95 is provided with a separable jawed clutch 95', and is adapted to be coupled to a clutch member on the hub or shaft of a sprocket wheel 115, connected by a chain 116 with a sprocket wheel 117, fixed upon the end of a parallel transverse shaft 118, journaled in bearings at the ends of the cross-bed 10', whereby the said shaft 118 is directly actuated by the main transmission shaft. The shaft 118 is splined or key-seated from end to end, and mounted so as to slide thereon, but to rotate therewith, is a worm 119, maintained in a relatively fixed position in the spud carriage 91, so as to participate in the transverse sliding movement of the latter. A shaft 120, arranged longitudinally of the car, is journaled in the spud carriage, and carries at one end a worm gear 121, in engagement with and rotated by the said worm 119. Intermediate its journaled ends, the shaft 120 is provided with a spud pinion 122, which engages a rack 123, on one of the faces of the spud or boom 90.

A U-shaped yoke 124, or other arrangement of a device, is mounted to turn upon the shaft 122, the yoke embracing and guiding the spud and holding the rack 123 in mesh with the pinion 122, this arrangement

permitting the spud to swing in the space between the cross beams or track 92 and 93, with the shaft 120 as its axis, in a vertical plane transversely of the car. A standard 5 125, rising from the spud carriage 91, has journaled at its upper end a short shaft 126, having on its forward end a pinion 127, in engagement with a segmental rack 128, attached to the U-shaped yoke which guides 10 the spud. A hand wheel 129 is attached to the other end of the shaft, so that by rotating the hand wheel, the spud may be positioned at any appropriate angle or inclination. A friction brake 130, at one end of a 15 spring 131, attached to the spud carriage, exerts a constant braking pressure upon the hand wheel to prevent its rotation under the weight of the spud, and hold the spud 90 in the position in which it has been 20 placed, and so prevent its voluntary movement. The cross-beams or tracks 92 and 93, are formed as flanges which project toward each other and form guides which enter channels in the opposite sides of the spud 25 carriage 91, and constitute a long bearing of ample thrust resisting power when the weight of the raised track is thrown onto the spud 90.

The separable jawed clutch 95', forming 30 the connection of the main transmission shaft 95 and the sprocket wheel 115, serves to transmit the motion of the said shaft 95 through the said sprocket wheel to the spud 90. The clutch is operated to transmit the 35 motion by means of a lever 136 pivoted at one end, and connected at the other by a link 137, which is adapted to be connected to the hand lever 110, so that the clutch may be operated to effect the transmission of power to actuate the spud. On the fixed 40 shaft 111², before referred to, is loosely mounted a second arm 111⁵, to which the other end of the link 137 is connected. The arm 111⁵ is provided with a stud 111⁶, which 45 likewise is adapted to enter the hole 110¹ in the hand lever 110, when the latter is thrown toward the rear of the car, and in the following movement of the said lever to the left or right the clutch 95' will be engaged 50 or disengaged. As shown in Fig. 5, the hand lever 110 is disposed between the arms 111⁴ and 111⁶, so that movement one way or the other in the direction of the shaft 111², will effect the desired engagement with 55 either arm, and when not engaged with either of the said arms, the said lever stands in its neutral position. Suitable devices for yieldingly holding the said lever in its neutral position may be provided.

60 When the car has been moved to that section of the track upon which it is desired to operate, and the spud properly "spotted" or located with relation to the space between two cross-ties, the brakes will be set and the car driving gear thrown out. The rail 65

clamping devices will then be operated, as hereinbefore described, and the car will be clamped to the rails.

Transverse movement of the spud carriage. 70

It is very frequently desirable to adjust the position of the spud widthwise of the car, as a preliminary operation, before raising the track.

To effect a quick traverse of the spud carriage 91, the latter is provided with a nut 145, which is in engagement with a rotatable screw shaft 146, journaled at its ends in the frame of the car, and carrying a sprocket wheel 147, over which, and an idler sprocket wheel 148, a sprocket chain 149, is passed. A traverse arm 149' is journaled at one end on the traverse screw shaft, and carries at its other end the said idler sprocket 148. The free end of the said traverse arm is supported by a spring 150, and the arm is adapted to be depressed by pressure of the foot. The main transmission shaft 95 has mounted thereon, a rotating but normally inactive sprocket wheel 151, which is arranged in the line of movement of the said sprocket chain. By depressing the traverse arm, the lower run of the sprocket chain is brought into engagement with the sprocket wheel 151 on the main transmission shaft, and the motion of the 80 said sprocket wheel 151 is imparted to the sprocket chain, and rotation given to the screw shaft 146. By this means, a quick traverse of the spud carriage is effected, and the spud is instantly brought to the desired 85 position for action. The traverse of the spud carriage ceases when the foot pressure is withdrawn, as the spring 150 immediately restores the traverse arm 149 to its inoperative 90 position.

In adjusting the position of the spud 90 with relation to the track, the operator will locate it so as to obtain the best results. The spud may set at any angle desired by simply turning the hand wheel 129, and when set at an angle from the perpendicular, the track will be thrown to the side desired. By running down the spud, the track will be raised and thrown automatically and without any actual canting of the spud, apart from that which follows its own voluntary action under the weight which it carries. The extent to which the raised track will be thrown will depend upon the angle at which the spud is made to stand at the time of the engagement 115 of the shoe 94 thereon with the roadbed and the extent of the elevation of the track. These are matters to be left to the judgment of the operator of the machine. I have found that when the spud 90 is truly perpendicular, there is an uncertainty as to which way the track will be thrown. Hence, the desirability of inclining the spud before operating the same, when the track is to be thrown. But when it is desired merely to raise the 120 125 130

track, the spud will be made to stand perpendicularly, and when the track has been elevated, the power may be cut off in the operation of the transmission brake, shown in Fig. 5, and the track will be held in suspension as long as the braking pressure remains constant.

Lifting and throwing the track.

10 With the spud 90 positioned as desired between two cross-ties of the track and the shoe 94 pressing upon the roadbed,—or it may be a mattress under some conditions,—the spud may now be forced downwardly to lift 15 the track. With the main transmission shaft unclutched from the car driving gears and the clutch member 106 in its neutral position, the main transmission shaft is now clutched to the primary driving shaft 16, 20 so as to press the spud 90 through its shoe against the roadbed.

A transmission brake shaft 155 extends from side to side of the car, and at a point within easy reach of the operator is provided 25 with a foot-operated brake lever 156, upon which a downward pressure may be exerted to give a partial rotation in one direction to the said shaft. The said main transmission shaft is provided with a brake drum 158 upon which bears a friction band 158, normally engaging the drum by the action of a contracting spring 159, and serving to restrain the rotation of the said shaft at the times that it is at rest.

30 The right end of the transmission brake shaft 155 is provided with a fixed radial arm 160, to which is connected the slotted end of a link 161, the other end of which is connected to one arm of a bell-crank 162, pivoted upon the frame or casing of the engine, and the other end of which is connected by a link 163 to the elements operating to control the clutch 164, coupling the sprocket 18 to the shaft 15 of the engine. A contracting spring 35 165, connected at one end to the arm 160 of the transmission brake shaft and fixed at the other, and a confined expansion spring 166, upon the link 163, act to reverse the transmission brake shaft when pressure on the brake lever 156 is released, disengaging the engine clutch 164 and applying the brake band 158 to the drum 157 of the main transmission shaft 95.

40 It may be here noted that propulsion of the car and rotation of the main transmission shaft, and movement of the parts operated from the latter, is effected only during the time that the transmission brake lever 156 is held in its depressed position so as to release the transmission brake and clutch the sprocket 18 to the shaft of the engine, and that upon the release of pressure upon the brake lever 156, the engine clutch 164 is disengaged and the braking pressure applied 45 to the drum on the main transmission shaft.

The ends of the transmission brake band are connected to a lever 170 at two points, so that as the said lever is depressed, the brake band is caused to tighten about the drum 158 on the main transmission shaft. At its free end, the lever 170 is connected to an adjustable link 171, the other end of which is connected to one end of a short lever 172, pivoted intermediately upon a stud set in a bracket 173. The free end of the lever 170 is also connected to the bracket 173, through the contracting spring 159, before referred to, and an eyebolt 174, the latter having provisions for adjusting the tension of the said spring. The normal action of the spring 159 is to apply the band to the drum on the main transmission shaft with a braking pressure. The transmission brake shaft 155, has secured thereon an arm 175, threaded for adjustment transversely in which is a screw 176, having an anti-friction roll journaled in its end. The said roll is adapted to bear upon and move over the other end of the pivoted short lever 172, so that in the depression of the transmission brake lever 156, the near end of the short lever is likewise depressed and rocked about its central pivot. In this action, the link 171 exerts an upward thrust upon the brake lever 170, against the force of the spring 159, and releases the braking pressure of the band upon the drum on the main transmission shaft 95.

50 In practice, one end of the brake band 158 is connected to a block 180, to which the brake lever 170 is pivoted axially of the shaft 95, and the other end of the brake band is connected to a block 181, transversely perforated for the reception of a link 182, to the rear end of which the brake lever 170 is connected at its second point of connection, which is its pivoting point. The link 182 passes through a guide 183, against which jam nuts may be adjusted to limit the longitudinal movement of the link 182, and so stabilize the pivotal movement of the brake lever 170, when the braking pressure is released. An expansion spring 184, confined about the link 182, and between the guide 183 and the inner face of the block 181, will be compressed by the pull on the link 182 when braking pressure is applied, and will have a tendency by expansion to open the brake band 158, when such pressure is relaxed. At the under side of the brake drum, and at about the middle of the brake band, a depending yoke 185 is attached to the latter. In the said yoke an expansion spring 186 is confined by the head of a pin 187, the lower threaded end of which is provided with adjustable jam nuts engaging the under side of a part of the framework of the machine, which is perforated for the guidance of the said pin, and by which it is retained in fixed vertical position. When the braking pressure is re-

laxed, the spring 186 will act to withdraw the brake band from the drum.

The connection between the upper end of the link 171 and the brake lever 170, is such as to allow free motion, and the said brake lever is provided with an auxiliary brake pedal 188, which may be utilized to augment the braking pressure applied through the devices which have been described, and 10 so exert a more effectual braking action on the main transmission shaft 95.

It is desirable, while the main transmission shaft 95 is operating to transmit functions to its connected parts, that the gear 15 connections between the said shaft and the primary driving shaft 16, be maintained against accidental disconnection. In order to effect this, as by locking the splined clutch member 101 in engagement with the gear 20 with which it is co-operating at the time, I make use of the locking lever 112¹, before referred to. The connections whereby the said lever is operated from the hand lever 112, have already been described. The lower 25 end of the locking lever 112¹, which operates the clutch member 101, is provided with an extension 112³, which in oscillations of the said locking lever, will occupy positions alternately at the sides of the path 30 of vertical movement of a dog 112⁴, secured upon the transmission brake shaft 155. Therefore, when the transmission brake lever is depressed, the dog 112⁴ will intersect the path of movement of the said projection 35 112³, and prevent movement of the clutch member 101 so long as the main transmission shaft is rotating.

The pin and slot connection between the arm 160 on the transmission brake shaft 40 and the link 161, will permit a slackening of the braking pressure before the engine clutch is thrown in.

With the transmission clutch 95' being coupled, it is necessary only for the operator to step on the transmission brake lever 45 156, holding it depressed for the time necessary to lift the track to the extent desired, when an automatic shift of the track will take place instantly, the spud 90 tilting in 50 such action. The main transmission shaft 95 will cease to rotate, and the engine be unclutched upon relaxation of the pressure upon the transmission clutch lever 156. The splined clutch member 101 may now be shifted 55 so as to reverse the rotation of the main transmission shaft, then in a repeated depression of the clutch lever 156, the spud 90 will be elevated for another operation.

60 *Holding the spud against downward creeping during the travel of car.*

When the car is travelling, the attendant vibrations of the spud and the weight of the latter, are conducive to the downward creeping 65 of the latter, and this, if not restrained

or closely watched, may be productive of disaster, if the lower end of the spud be brought into contact with an obstruction.

To guard against such an exigency, I have provided an automatically operating device 70 which, though ineffective in the normal operation of the machine, will instantly become effective when the transmission clutch 95' is thrown out by the transmission clutch lever 136, before referred to. Centrally pivoted in a mounting 190, is a lever 191, one end of which is formed as a brake shoe 192. The opposite end of the said lever is provided with a contact piece 193, which may be held in adjusted position by 80 a set screw, threaded into the end of the lever. When the transmission clutch lever is thrown by the movement of the hand shifting lever 110, the transmission brake lever 136, formed with a cam 194, will pass under the contact piece 193, and press the brake shoe into engagement with the hub of the sprocket 115, and hold the same against rotation. The braking pressure maintained at that point is sufficient to overcome the creeping tendency. Ordinarily, the rotation of the shaft 120 of the spud carriage 91, is prevented by the character of the lock against rotation afforded by the worm 119 engaging the worm gear 121. 95

Fig. 10 shows the device for retaining the splined clutch member 106 in either of its three positions. This device consists of a spring pressed plunger 196 provided with a central depression for effecting the neutral position of the clutch member, flanked by lateral depressions for effecting both of the operative positions of the said clutch member, the said depression being adapted to receive in alternation a roll carried by the locking lever 111¹ of the clutch shaft. 105

The numeral 200, Fig. 1, indicates the starting crank for the motor. The throttle control may be arranged at any convenient point, preferably upon the hand lever 110. 110

The details of construction may be varied from what is shown, without departing from the spirit of my invention.

Having thus described my invention, what I claim and desire to secure by Letters Patent of the United States, is:

1. In a track raising and shifting machine, a floating clamp beam, rail clamps supported thereby, and means for raising the beam to cause the clamps to engage the rail.

2. In a track raising and shifting machine, a floating clamp beam, thrust bars for stabilizing the said beam, rail clamps supported by the said beam, and means for raising the said beam to engage the said clamps with the rail.

3. In a track raising and shifting machine, a car and frame, a floating clamp beam and rail clamps depending therefrom,

- thrust bars attached at one end to the frame and to the clamp beam at the other, to stabilize the beam, means for moving the beam to engage the clamps with the rail, 5 and means for shifting the beam and rail clamps clear of the rails, to permit free movement of the car.
4. In a track raising and shifting machine, a car and frame, a floating clamp beam, rail clamps supported thereby, means for stabilizing the vertical movements of the clamp beam, means for raising the beam to cause the clamps to engage the rail, and means for relieving said raising means of the 15 weight of the track.
5. In a track raising and shifting machine, a car and frame, means for clamping the car to the track, a vertically movable spud, a transversely moving carriage for 20 the spud, means for moving the spud to lift the track, and means engageable with the spud moving means for moving the carriage.
6. In a track raising and shifting machine, a car, means carried thereby for 25 clamping the car to the track, a vertically movable spud for raising the track, a transversely movable carriage for the said spud, a screw shaft for operating the same, a transmission shaft, and means engageable 30 with the transmission shaft for rotating the said screw shaft.
7. In a track raising and shifting machine, a frame, a transversely movable spud carriage, and a vertically movable spud 35 pivotally supported therein, means on the carriage for changing the angle of the said spud, and means also on the carriage for holding the spud in its changed position.
8. In a track raising and shifting machine, a car, a floating clamp beam, rail clamps connected thereto, means for lifting the clamp beam to cause the clamps to engage the rail, said lifting means comprising a shaft with a lever and short arm thereon, 45 and a curved link connection with the short arm, whereby in the lifting throw of the lever, the pivotal connection of the curved link with the short arm passes the center line of the shaft.
- 50 9. In a track raising and shifting machine, a car and frame, a power plant supported thereon, a main driving shaft driven by the power plant, a car driving shaft, a main transmission shaft, means for coupling the main transmission shaft to the main driving shaft, means for coupling the main transmission shaft to the car driving shaft, and a track raising spud operated from the main transmission shaft.
- 55 10. In a track raising and shifting machine, a car and its frame, a vertically movable clamp beam carried by the car frame, means for stabilizing the clamp beam against lateral movement, rail clamps supported by
- the clamp beam, means for actuating the 65 clamps through the said beam to engage the track and clamp the car thereto, and means for raising the car and track.
11. In a track raising and shifting machine, a car and its frame, a floating clamp beam carried by the car frame, means for stabilizing the said beam against lateral movement, rail clamps supported by the said beam, toggle devices intermediate the said beam and the clamps for actuating the latter 75 to engage the rail oppositely when the beam is lifted, means for raising the beam to effect such engagement, and means for raising the car and the track.
12. In a track raising and shifting machine, a car and its frame, a vertically movable clamp beam carried by the car frame and having rail clamps at its ends, means for moving the beam to engage the clamps with the track and clamp the car thereto, 85 and means for raising the car and the track.
13. In a track raising and shifting machine, a car and its frame, a clamp beam movable vertically with relation to the car, rail clamps upon the said beam, means for moving the beam to engage the clamps with the track and clamp the car thereto, and means 90 for raising the car and track.
14. In a track raising and shifting machine, a car and its frame, a clamp beam 95 having rail clamps, means for lifting the beam to engage the clamps with the track and clamp the car thereto, means for raising the car and the track, and means between the frame and the clamp beam to prevent lateral movement of the clamp beam, whereby the car wheels are relieved from side thrust when the track is shifted.
15. In a track raising and shifting machine, a car and its frame, a vertically movable clamp beam and rail clamps depending therefrom, means for lowering the clamp beam to position the clamps for engagement with the track, means to disengage the clamps from the track, and means to raise 110 the beam and the clamps clear of the track, to permit the car to be moved.
16. In a track raising and shifting machine, a car and its frame, means for clamping the car to the track, a spud or boom and means for depressing the latter to raise the track and the car, a transversely movable spud carriage, a normally idle screw shaft engaging the carriage, a constantly rotating shaft, and means for transmitting at will 120 the movement of the rotating shaft to the idle shaft, to position the spud carriage.
17. In a track raising and shifting machine, a car and its frame, means for clamping the car to the track, a spud or boom and means for depressing the latter to raise the track and the car, a transversely movable spud carriage, a normally idle screw shaft 125

- engaging the carriage, a constantly rotating shaft, and means for transmitting through foot-operated devices the movement of the rotating shaft to the idle shaft, to position 5 the spud carriage.
18. In a track raising and shifting machine, a car and its frame, means for clamping the car to the track, a spud or boom and means for depressing the same to raise the 10 track, means for turning the spud to an angular position, and means for retaining the spud in such position preparatory to a track raising operation.
19. In a track raising and shifting machine, a car and its frame, means for clamping the car to the track, a spud or boom and means for depressing the same to raise the track, and means apart from its actuating means for holding the spud against downward movement during the travel of the car. 15 20

In testimony whereof, I have signed my name at Milwaukee, this 24th day of October, 1925.

H. H. TALBOYS.
